TILTING CHAIR SEAT AND BACK REST

William J. Sengpiel, Buffalo, N. Y., assignor to
The Sikes Company, Buffalo, N. Y.

Application February 19, 1946; Serial No. 648,580

7 Claims. (Cl. 155—77)

1

2

My invention relates generally to chairs of the type having a tilting seat and back and in particular to a chair having seat and back elements which automatically adjust themselves relatively as the back is inclined, and commonly referred to as a posture chair of the general type shown and described in U. S. Patent No. 1,909,018 issued to me on May 16, 1933.

It has been an object of the present invention to provide a chair of the above type which is an improvement over prior chair arrangements including that of my patent aforesaid. Another object is to provide a chair in which the seat and the back are interdependent in their pivotal movements and in which the back will move angularly at an accelerated rate as compared with the angular movement of the seat, and thus assume a position relative to the seat which is most natural and comfortable for the occupant.

A further object has been to provide a chair having a back so pivotally mounted that its angular movements shall correspond substantially to the movements of the occupant's body, whereby movements of the chair back relative to the occupant's body, such as would produce creeping of the occupant's clothing, will be substantially prevented.

It has also been an object to provide a chair of this type, having a back so mounted as to permit an ample amount of tilting movement in relation to the movement of the seat.

These and other objects which will be apparent to those skilled in the art have been accomplished by the device shown in the accompanying drawings, of which:

Fig. 1 is a side, sectional elevation of a chair embodying my invention;

Fig. 2 is a similar view showing the parts in their tilted positions;

Fig. 3 is a plan view of the mechanism embodying my invention;

Fig. 4 is an enlarged transverse fragmentary sectional view taken on line IV—IV of Fig. 3; and

Fig. 5 is an enlarged fragmentary sectional view taken on line V—V of Fig. 3.

Referring to the drawings, I have shown my invention as applied to a chair having the usual supporting pedestal 10 which is adapted to receive and adjustably support a spindle 11. The spindle 11 carries at its upper end a head 12 having spaced side walls 13 connected by a lateral wall 14. Angle-iron arms 15 are rigidly secured to the side walls 13 of the head and they are extended forwardly having their outer ends preferably flared outwardly and pivotally united to the forward

ends of seat flanges 16 by pivots 20. The seat flanges which extend from the front to the back portions of the seat 21 are secured to the bottom surface thereof and are in spaced relation with each other.

The chair is provided with a back 22 having side members 23 to the upper ends of which is secured a back rest 24 and to the lower ends of which is secured a curved cross bar 25. A back bracket 26 is provided having spaced side arms 30 extending forwardly and pivotally mounted upon a pivot rod 31 carried by the seat flanges 16, suitable spacers 32 being provided on the rod to maintain the bracket in central position. Carried by the head 12 is a bell crank member 33 which is pivotally mounted upon a pivot rod 34 supported by the side walls 13 of the head. This member is provided with an upstanding bolt arm 35 and with a rearwardly and upwardly inclined slide arm 36. The slide arm is so arranged that it extends across and is located below the pivot rod 31 of the back bracket 26, and a slide block 40 is located between the slide arm and the rod. The block is rigidly secured between the side arms 30 of the bracket 26 and is therefore pivotally movable therewith. The slide arm is provided with a smooth upper surface 41 acting as a bearing for the block. Grooved guideways 42 are preferably formed at the longitudinal edges of the arm, and the block is provided with guide flanges 43 for coaction with said guideways to keep said block in guiding alignment. The pivot rod 31 extends through the block and anti-friction rollers 44 are mounted upon the rod and disposed within recesses 45 formed through the block. The slide arm of the bell crank member is formed with a longitudinal slot 46 for the sliding reception of fastening means 50 passing through the block and into a slide plate 51 disposed adjacent the lower face of the slide arm 36, whereby the block 40 and the arm 36 are slidably united.

In order to resiliently retain the seat and back in their normal positions, I provide a helical spring 52 which is mounted upon a bolt 53, having one end of its ends bearing against the lateral wall 14 of the head and the other end bearing against a washer 54 held in place upon the bolt by means of an adjusting nut 55 screw-threaded to the outer end of the bolt. The bolt passes through an elongated aperture 56 formed in the wall 14 and also through an elongated aperture 60 formed in the upper end of the bolt arm 35 of the bell crank member. The head 61 of the bolt is located on the side of the arm 35 which is opposite the

wall 14 and a laterally arranged V-shaped ridge 62 is formed on the surface of said surface of the arm in line with the aperture for the tilting engagement of the bolt head.

Thus, it will be understood that whenever a person sits upon the chair of the invention there will be thereby applied against the rear portion of the seat a downward pressure which tends to initially pivot the seat back and down about the pivots 20-20, thereby carrying the chair back 22 along with the seat 21. Then, whenever the chair occupant desires to lean backward to some more comfortable semi-reclining position, this is accomplished by the application of pressure by the occupant directly rearwardly against the chair back 22. Such pressure against the chair back 22 levers the bracket 26 downwardly about the pivot 31 and this in turn rocks the bell crank 33 downwardly about its pivot 34; the change in the distance between the pivots 31 and 34 being permitted by sliding of the block 40 upon the bell crank arm 36. Coincidentally therewith the downward pull against the pivot rod 31 depresses the rear ends of the seat flanges 16 which pivot upon their bearings 20-20 relative to the stationary head 12 and angle arms 15-15.

It will be understood that this levering motion of the chair back applies additional stress to the spring 52 through the bell crank 33, so that when the rearward pressure against the chair back is subsequently released the spring 52 will return the chair to its normal upright position. Thus, it will be understood that the mechanism applying the force of the spring 52 for the purpose of resisting tilting of the chair seat 21 is directed through the bell crank device 33 and is located at substantially the fore and aft center position of the chair seat, and because of the tension of the spring the chair seat normally tends to remain substantially level whether occupied by a heavy or light weight person. However, in the case of either person, addition of backward pressure against the chair back 22 by the occupant immediately overcomes the pressure of the spring upon the seat-moving mechanism and sets into motion the bell crank levering device which simultaneously tilts the chair seat 21 downwardly to a predetermined degree while lowering the chair back 22 to a tilted angle, and at the same time displacing the chair back 22 downwardly relative to the rear edge of the chair seat.

Thus, it will be understood that, as the chair assembly tilts backwardly, the distance between the occupant's hip axis and the region of frictional contact between his clothing at the shoulder portions of his body and the chair back pad 24, is reduced to a minimum throughout all angular motions of the chair, and that this substantially avoids creeping and wrinkling of the occupant's clothing incidental to movements of the chair back. Prior art arrangements which embody no such bodily displacement of the chair back relative to the chair seat invariably cause wrinkling of the occupant's clothing in connection with the normal use of this type chair.

During the tilting movement above described, the compressible pivot rod 31 will approach the plane of the pivot rod 34, and the block 40 will slide upon the arm 36 of the bell crank member and will be moved toward the pivot rod 34 thus shortening the effective length of the arm. This ever increasing shortening of the arm causes it to oscillate about its pivot at an accelerated rate and consequently tilts the back at a corresponding rate, thus placing the seat and back in the

position which is recognized as the most natural and comfortable position for the occupant. Obviously, the degree of movement of the back and seat will depend upon the pressure placed upon the back thereof, and the tension of the spring 52 which may be controlled by manual adjustments of the nut 55.

Obviously, some modifications of the details herein shown and described may be made without departing from the spirit of the invention or the scope of the appended claims, and I do not therefore wish to be limited to the details herein shown and described, the form shown being merely the preferred embodiment thereof.

15. What is claimed is:

1. A chair comprising a seat, a support for the seat, means pivotally connecting said seat to said support, spring means tending to oppose tilting movement of said seat in one direction, a back, means pivotally connecting said back at its lower end to the rear end portion of the seat, bell crank means pivotally carried by said support and having one arm thereof engaging said spring means, and means rigidly carried by said back for slidably connection with the other arm of said bell crank for causing relative pivotal movement of said back and seat as said back is tilted back and forth upon its pivotal support.

2. A chair comprising a seat, a support for the seat, means pivotally connecting said seat to said support, spring means tending to oppose tilting movement of said seat in one direction, a back, a back bracket attached to said back and pivotally carried by the rear portion of said seat, a bell crank member pivotally carried by said support and having a bolt arm coacting with said spring means, said bell crank having a slide arm, means rigidly carried by said bracket and slidably engaging said slide arm for causing tilting movement in unison of said seat and said back under the influence of said spring means.

3. A chair comprising a seat, a support for the seat, means pivotally connecting said seat to said support, spring means tending to oppose tilting movement of said seat in one direction, a back, a back bracket attached to said back and pivotally carried by the rear portion of said seat, a bell crank member pivotally carried by said support and having a bolt arm coacting with said spring means, said bell crank having a slide arm, slidably connecting means between said back bracket and said bell crank slide arm for causing tilting movement in unison of said seat and said back under the influence of said spring means.

4. A chair comprising a seat, a support for the seat, means pivotally connecting said seat to said support, spring means tending to oppose tilting movement of said seat in one direction, a back, a back bracket attached to said back and pivotally carried by the rear portion of said seat, a bell crank member pivotally carried by said support and having a bolt arm and a slide arm, a slide block rigidly carried by said bracket and slidably engageable with said slide arm to permit angular movements of said bell crank and said bracket to be transmitted to each other, and means connecting said bolt arm to said spring means, whereby tilting movement of said seat and said back will be influenced by said spring means.

5. A chair comprising a seat, a support for said seat, seat flanges rigidly carried by the seat, rigid arms carried by and extending forwardly from said support, a forward fixed pivotal con-

nection carried by said arms for pivotally mounting the forward end portion of said seat, a rear depressible pivotal connection carried at the rear end portion of said seat, a back pivotally connected to said depressible pivot connection, a bell crank pivotally carried by said support and having its pivotal connection below a line drawn between the pivotal connections carried by said seat and said arms, spring means coacting with said bell crank to oppose tilting movement of said seat and said back, and slidable means connecting said back with said bell crank for permitting said seat and said back to tilt in unison and relatively to each other.

6. A chair comprising a seat, a support for the seat, means pivotally connecting said seat to said support, spring means tending to oppose tilting movement of said seat in one direction, a back, a back bracket attached to said back and pivotally carried by the rear portion of said seat, a bell crank member pivotally carried by said support and having a bolt arm and a slide arm, said slide arm being formed with a longitudinal slot, a slide block rigidly carried by said bracket and slidably engageable with the upper surface of said slide arm to permit angular movements of said bell crank and said bracket to be transmitted to each other, a slide plate mounted on the under surface of the slide arm, means passing through the arm slot for connecting said plate to said block, and means connecting said

bolt arm to said spring means, whereby back and forth tilting movement of said seat and said back will be influenced by said spring means.

7. A chair comprising a seat, a support for the seat, means pivotally connecting said seat to said support, spring means tending to oppose tilting movement of said seat in one direction, a back, a back bracket attached to said back and pivotally carried by the rear portion of said seat, 5 a bell crank member pivotally carried by said support and having a bolt arm and a slide arm, a slide block rigidly carried by said bracket, anti-friction rollers carried by said block for rolling engagement with the upper surface of said slide 10 arm, means for maintaining said rollers in contact with said slide arm, and means connecting said bolt arm to said spring means, whereby back and forth tilting movement of said seat and said back will be influenced by said spring 15 means.
